(57) **CLAIM**

We claim the ornamental design for a tooth adapter of
excavator bucket, as shown and described.

DESCRIPTION

FIG. 1 is a perspective view of a tooth adapter of excavator
bucket, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a reference view thereof showing an example
configuration of use in which the tooth adapter of excavator
bucket may be fixed to a separate tooth to be applied to an
excavator bucket body while a wear cap for an excavator
bucket is coupled to grooves on both sides.

The dash-dash broken lines in the drawings show portions of
the tooth adapter of excavator bucket that form no part of the
claimed design. The dot-dash broken lines in the drawings
depict boundaries of the claim and form no part thereof.
